UNITED STATES PATENT OFFICE.

CHARLES E. LINCOLN, OF BOSTON, MASSACHUSETTS.

EXERCISING APPARATUS.

1,412,691.

Specification of Letters Patent. Patented Apr. 11, 1922.

Application filed May 3, 1921. Serial No. 466,505.

To all whom it may concern:

Be it known that I, CHARLES E. LINCOLN, a citizen of the United States, and a resident of Boston, in the county of Suffolk and State of Massachusetts, have invented a new and Improved Exercising Apparatus, of which the following is a full, clear, and exact description.

This invention relates to improvements in exercising apparatus, an object of the invention being to provide a resilient device which may be held in the hand of an operator and squeezed to exercise the muscles of the fingers and wrists.

Another object of the invention is to provide an exercising apparatus of this character, which may be conveniently carried in the pocket of a user, which will take up a comparatively small space, which will be simple and practical in construction, strong and durable in use, and exceedingly inexpensive to manufacture.

With these and other objects in view, the invention consists in certain novel features of construction and combinations and arrangements of parts as will be more fully hereinafter described and pointed out in the claims.

In the accompanying drawings:—

Figure 1 is a perspective view illustrating the manner of use of my improved exercising apparatus;

Figure 2 is a view in elevation thereof; and

Figure 3 is a view in longitudinal section therethrough.

Referring in detail to the drawings, 1, 1 represent a pair of hollow pneumatic balls. These balls are enclosed within a casing 2 which may be of any flexible material, but

which is preferably of thin rubber or leather.

A relatively stiff collar 3 encircles the cas-

ing 2 and is interposed between the balls 1, the collar serving to space the balls apart. Although I do not wish to be limited to any particular material for the collar, I have found that one or more convolutions of adhesive tape are effective in this connection.

The manner of use of the apparatus is illustrated in Figure 1. The apparatus is placed in the palm of the hand and squeezed. One of the balls is squeezed against the palm of the hand by the middle finger, fourth finger and little finger of the operator and the other ball is squeezed between the index finger and the thumb. The device will prove very effective for exercising all of the muscles of the hand and wrist.

Although I have illustrated one of the preferred embodiments of my invention, it will be apparent that various slight changes and alterations might be made in the general form and arrangement of the parts described without departing from the invention and hence I do not wish to limit myself to the precise details set forth, but shall consider myself at liberty to make such slight changes and alterations as fairly fall within the spirit and scope of the appended claims.

I claim:

1. An exercising apparatus of the character described, including an elastic casing, a pair of rubber balls in the casing, and means spacing the rubber balls apart, said last mentioned means comprising a relatively stiff collar restricting the central portion of the casing.

2. As a new article of manufacture, an exercising apparatus including a flexible casing, a pair of resilient balls of equal size in the casing, and a collar encircling and restricting the central portion of the casing and spacing the balls apart.

CHARLES E. LINCOLN.
